UNITED STATES PATENT OFFICE.

HOWARD PARKER, OF BELLOW'S FALLS, VERMONT.

PAPER-MAKING MACHINE.

SPECIFICATION forming part of Letters Patent No. 693,897, dated February 25, 1902.

Application filed June 7, 1901. Serial No. 63,507. (No model.)

To all whom it may concern:

Be it known that I, HOWARD PARKER, a citizen of the United States, and a resident of Bellows Falls, county of Windham, State of Vermont, have invented certain new and useful Improvements in Paper-Making Machinery, of which the following is a specification.

The drawing represents a perspective view 10 of an apparatus embodying my invention.

It is common practice in paper-making to suspend the pulp, which has been divided into very fine particles, in some liquid, preferably water. The finely-divided particles of 15 pulp in the solution are very buoyant, and it is essential that they be collected evenly and regularly, preferably into a sheet, for storage or shipment or further working. In the tank which contains the pulp solution it is common 20 practice to mount a revoluble roll having a pervious periphery. As this roll revolves the pulp by virtue of its buoyant character is deposited in a sheet of more or less thickness on this roll. It is important that 25 as much as possible of the moisture and water in the pulp as it forms into a layer on the roll be extracted; and my invention relates to a novel method of partially drying the pulp while it is on the aforementioned roll.

In the drawing, A denotes the tank, and B the roll mounted therein. As the roll rotates 30 in the direction of the arrow when it enters the solution the pulp immediately begins to be deposited on its surface, and this deposition continues until the surface of the roll leaves the solution. The roll is divided into longitudinal compartments by the partitions C. In order to extract the water and moisture 35 from the pulp as it forms on the roll, I provide a suction apparatus arranged to exert its force on the compartments in the roll as they leave the solution in the tank A. A preferred form of accomplishing this result

is shown in the drawing, which consists of the stationary plate D, held in position by the 45 angle-irons E, which are secured to the end of the tank, as at F. This plate has formed in it the recess G, to which a suction-pipe may be connected, as at H. The recess may be made of such size and shape as to communicate with any number of compartments desired, but preferably four, as shown in the drawing, the compartments as they pass from the solution being almost immediately subjected to the suction action and the moisture 55 being thereby withdrawn from the pulp on the roll. Springs I, located between one flange of the angle-irons E and the plate D, keep this plate pressed against the end of the revolving cylinder and successfully prevents 60 the passage of air between the plate and the end of the cylinder into the compartments which are being subjected to the suction action.

I claim as my invention—

1. In combination in a machine of the class specified the tank, the roll revolvably mounted therein, and compartments arranged in the interior of the roll, a suction apparatus and a stationary plate forming a part of said apparatus arranged to close the ends of part 70 only of the compartments as they pass said plate, substantially as described.

2. The combination in a machine of the class specified with the tank, the roll revolvably mounted therein, and compartments in the interior of said roll, of a stationary plate adapted to close the ends of one or more of the compartments, and springs for holding 75 said plate in position, substantially as described.

HOWARD PARKER.
